UNITED STATES PATENT OFFICE

GEORGE L. WACKEROW, OF MELLETTE, SOUTH DAKOTA

END-GATE CONSTRUCTION

Application filed February 11, 1928. Serial No. 253,585.

This invention relates to an end gate construction for a wagon. It is common to have wagon box bodies equipped with end gates either of the swinging type or of a type 5 adapted to be slid bodily from the end of the sides of the wagon body. Such box wagon bodies often have their sides spread apart by the load carried therein. It will readily be seen that there is a great pressure on the sides 10 of the wagon body when fully loaded, especially if loaded with such material as grain. It also often happens with certain end gate constructions that the sides are pushed apart when the end gate is inserted.

15 It is an object of this invention, therefore, to provide a simple and efficient end gate construction by means of which the sides of the wagon body are held in proper position and kept from spreading on account of the load 20 in said body.

It is a further object of the invention to provide an end gate construction in which the end gate is slidable to position and has members thereon engaging with members on 25 the sides of the wagon body to hold the latter in proper position and prevent spreading thereof.

It is an object of the invention to provide an end gate construction comprising an end 30 gate having means thereon adapted to engage means on the wagon body to prevent spreading of the sides thereof and also to engage means on the sides of the body extension adapted to be placed on top of said body.

35 It is more specifically an object of the invention to provide an end gate construction comprising a box wagon body having platelike members secured to the sides of said body having offset portions extending rearwardly 40 and spaced slightly from the sides of said body, together with an end gate having platelike members secured thereto adjacent its ends adapted to be received between said first mentioned members and the sides of 45 said body, and means for holding said end gate in position.

These and other objects and advantages 50 of the invention will be fully set forth in the following description made in connection with the accompanying drawings, in which

like reference characters refer to similar parts throughout the several views and in which:—

Fig. 1 is a rear view of the wagon body with the end gate in position;

Fig. 2 is a horizontal section taken on line 2—2 of Fig. 1, as indicated by the arrows; and

Fig. 3 is a vertical section on line 3—3 of Fig. 1, as indicated by the arrows and shown on an enlarged scale.

Referring to the drawings, a wagon body of the box type is shown, comprising the floor or bottom 5, and the side walls 6 extending upwardly therefrom. A supporting member 7 extends beneath the bottom 5 adjacent the end thereof and is supported at its ends which project beyond the sides 6 by the brackets 8 bolted thereto and to the said sides. An extension of the wagon box body 70 is shown in Fig. 1, which will comprise a rectangular box having the side walls 9, said box being of the same size as the wagon box so as to set directly on top of the same. Said sides are shown as being connected by the 75 angle bars 10 secured by the bolts 11. The side walls 6 have secured to the inner sides thereof, adjacent their rear ends, the platelike members 12. These members have portions directly in contact with said sides and bolted thereto by the spaced bolts 13. The members 12 also have the offset rear portions 12^a extending parallel to and slightly spaced from the sides 6. The extension box members 9 also have platelike members 14 secured to 85 the sides thereof, adjacent their rear ends similar to the members 12 and having similar offset rear portions 14^a.

An end gate 15 is provided, of the same height as the sides 6 and of a length adapted to substantially fit between said sides. Said end gate 15 has the angle members 16 secured at the ends thereof, having inwardly projecting sides or flanges, which, when the end gate is in closed position as shown in Fig. 2, fit between the offset portions 12^a and the sides 6. As shown in Fig. 3, the angle members 16 also fit within the offset portions 14^a of the members 14, which members project below the box 9 and down into the wagon box body. The 100

sides 6 have apertures 6^a therethrough, in the rear of the end gate 15, and plates 17 are secured to the inner sides of said sides 6, having apertures alining with the apertures 6^a. Angle plates 18 are secured to the rear side of the end gate 15, having rearwardly projecting flanges also provided with apertures alined with the apertures 6^a. A plate 19 is secured to the rear side of end gate 15 substantially at the center thereof, centrally of which is pivoted the lever 20 having a flat portion extending parallel to said plate and having a handle portion of considerable length. The end of said handle portion of the lever 20 has inwardly and outwardly bent ends 20^a and 20^b respectively. The lever 20 has pivotally secured thereto at equal distances from the pivot 21 by which it is pivoted to plate 19, the rods 22 extending laterally in opposite directions and passing respectively through the apertures in plates 18.

In operation, when the end gate is in its operative position closing the end of the wagon body, it is disposed as shown in Figs. 1, 2 and 3. At this time the inwardly projecting sides of the angle bars 16 pass within the space between portion 12^a of the plates 12 and the sides 6. It will thus be seen that the sides 6 are securely held in properly spaced relation and cannot be spread at their upper ends by any load that is carried in the wagon body. It will also be seen that if the sides should become spread somewhat when the end gate is removed, that they can be drawn together in proper position when the end gate is replaced. The flanges of the angles 16 can be engaged with the members 12^a at their lower ends and said members will thus be drawn inward as the end gate is swung upward to its closed position. When the end gate is in closed position, the lever 20 is swung as shown in Fig. 1 and thus projects the rods 22 through the plates 17 and into the apertures 6^a in the sides 6. When the rods are in this position, it will be seen that the lever 20 passes slightly beyond dead center so that there is no tendency for the same to swing to position withdrawing the rods 22. The lever 20 can be positioned with the projection 20^a extending above the rod 22. The said lever is thus firmly held in position with the end gate locked in place by the rods 22.

When it is desired to remove the end gate, the lever 20 will be released and swung in a counter-clockwise direction to the dotted line position shown in Fig. 1, when the rods 22 will be moved to the dotted line position shown in said figure. Said rods thus move out of engagement with sides 6 and plate 17 and the end gate can thus be withdrawn rearwardly.

From the above description it is seen that applicant has provided a very simple and very efficient construction of end gate and

one which will prevent the objectionable spreading of the sides of the wagon body. Not only is the wagon body kept from spreading, but the members 12 and 16 on the end gate strengthen these parts and provide a very durable and rugged construction. The members 16 also prevent spreading of the sides of the extension box 9 and tend to hold this box in place. Such extension boxes are commonly used when threshed grain is being hauled. The present invention is very efficient in positioning such a box and prevents spreading of the sides thereof.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:

1. An end gate construction having in combination, a wagon box body having a bottom and side walls and open at its rear end, members secured to the inner sides of said side walls adjacent their rear ends and having terminals spaced from said walls, an extension box having side and rear walls disposed on top of said box body, members secured to the inner side of said side walls of said extension box and projecting downwardly along the sides of said box body and also having terminal portions spaced from the walls of said box body and extension box, an end gate disposed between said walls of said box body, members secured to the inner side of said end gate adjacent the ends thereof adapted to engage with the members on the sides of said box body and on the sides of said extension box and being disposed between the same and the walls of said body to prevent spreading thereof, and means for holding said end gate in position.

2. An end gate construction having in combination, a wagon box body having a bottom and side walls and open at its rear end, platelike members secured to the inner sides of said side walls adjacent their rear ends and having offset rear portions spaced from and adjacent said side walls, an extension box having side walls disposed on top of said box body, platelike members secured to the inner sides of said walls of said extension box and having offset rear portions extending down into said box body along the sides thereof, an end gate adapted to be disposed transversely between the side walls of said box body, members secured to the inner side of said end gate adjacent the ends thereof having inwardly extending flanges adapted to pass between the side walls of said box body and the members thereon and between the side walls of the box body and the members on the sides of the

extension box, and means for holding said end gate in position.

3. An end gate construction having in combination a wagon box body having a bottom and side walls and open at its rear end, members secured to the inner sides of said walls adjacent their rear ends, an extension box having side and rear walls disposed on top of said box body, members secured to the inner sides of the side walls of said extension box and projecting downwardly along the side of said box body and vertically aligned with said first mentioned members respectively, an end gate disposed between the walls of said box body, means secured to the inner side of said end gate adjacent the ends thereof adapted to engage with said members on said box body and with said members on the sides of said extension box for preventing spread of both of said sides and means for holding said end gate in position.

In testimony whereof I affix my signature.

GEORGE L. WACKEROW.
